(57) **CLAIM**

The ornamental design for a roller device for squeezable tubes, as shown and described.

DESCRIPTION

FIG. 1 is a perspective, front and first side view of the roller device for squeezable tubes in accordance with the first embodiment of the Design;

FIG. 2 is a front view of the roller device for squeezable tubes of FIG. 1;

FIG. 3 is a rear view of the roller device for squeezable tubes of FIG. 1;

FIG. 4 is a top plan view of the roller device for squeezable tubes of FIG. 1, the bottom view being identical to the top plan view shown;

FIG. 5 is a first side view of the roller device for squeezable tubes of FIG. 1;

FIG. 6 is a second side view of the roller device for squeezable tubes of FIG. 1;

FIG. 7 is a perspective, front and first side view of the roller device for squeezable tubes of FIG. 1 shown in its environment;

FIG. 8 is a perspective, front and first side view of the roller device for squeezable tubes of FIG. 1 shown in its environment;

FIG. 9 is a perspective, front and first side view of the roller device for squeezable tubes in accordance with the first second of the Design, the top plan view and the bottom view thereof being identical to the view shown in FIG. 4, the first side view thereof being identical to the view shown in FIG. 5, the second side view thereof being identical to the view shown in FIG. 6;

FIG. 10 is a front view of the roller device for squeezable tubes of FIG. 9; and,

FIG. 11 is a rear view of the roller device for squeezable tubes of FIG. 9.

Broken lines are used to illustrate portions of the roller device other broken lines illustrate environmental subject matter that form no part of the claimed design.

1 Claim, 4 Drawing Sheets
